UNITED STATES PATENT OFFICE

2,601,652

AIR-CONDITIONED OPEN TOP DISPLAY CABINET

David Franklin Williams and James Donald Williams, Greenville, S. C., assignors to Williams Refrigeration, Inc., Greenville, S. C., a corporation of South Carolina

Application February 11, 1949, Serial No. 75,762

10 Claims. (Cl. 62—89.5)

1

The present invention provides an improved air-conditioned display case or stand for displaying and preserving perishable articles of food, such as fresh fruits and green vegetables, wherein the case has its display or supporting face directly open to the outside air and is free of enclosing side walls or front walls or top walls, and wherein means are provided for maintaining the commodities being displayed on the table in a cool and humidified condition.

The display stands of the general type to which this invention relates are provided customarily with a cooling coil around which the air to be employed for conditioning and preserving the commodities is circulated by forced circulation through the provision of a fan or blower which forces air from the outside around the refrigerating coil over the commodities being displayed. Such arrangements as are employed customarily have certain objections. Among such objections, there may be mentioned specifically high operating costs due to the power consumption required for the operation of the refrigerating coils and blowing means, lowered humidifying efficiencies through desiccation of the air by extraction of moisture by the refrigerating coils, and by warming effects on the circulating air due to atmospheric air being aspirated into the circulating air due to the velocity of the forced circulation.

The present invention has for one of its objects the provision of an air-conditioning and humidifying display case for perishable food commodities which eliminates the above-mentioned, and other objections, inherent in the customary constructions, by eliminating a system of forced circulation and providing a system of circulation which maintains the moisture content of the circulating air continuously substantially constant, and which causes the circulation of air in the cabinet and over the commodities without admixture therewith of any substantial amounts of outside atmospheric air.

A further object of the invention is to provide an improved construction of the above-indicated character wherein the commodities displayed are cooled below a spoilage temperature and are kept moist and hydrated by moisture condensed from the air circulating in the cabinet or case and in and around the commodities being displayed.

A still further object of the invention is to provide an improved means for effecting condensation of moisture contained in the air circulating within the case and in and around the display commodities, without the formation of ice, and for effecting utilization of the condensed moisture

2 for maintaining an effective hydration of the commodities.

A still further object of the invention is to provide an air-conditioned equipment of the indicated character wherein circulation of air is effected through the utilization of different specific gravities between relatively cooler and warmer air.

A still further object of this invention is to provide a display cabinet of the above-indicated type in which there is provided means for directing therein descending relatively heavy cool air currents laden with condensed moisture from the cooling coil in the cooling compartment, in and around the commodities being displayed and preserved, to the warm air compartment and back to the cooling compartment, and with a minimum of temperature change.

A still further object of the invention is to provide an open display case of the above-indicated character or type wherein the cool air circulating from the cooling coil over the commodities being displayed passes into the interior of the case by specific gravity alone, and without the aid of forced circulating means, and without any substantial intermixing with the warm atmospheric air.

A still further object of the invention is to provide an open display case having auxiliary display means adapted to enhance the display and appearance of the commodities.

A still further object of the invention is to provide a display case of the described type wherein maximum storage space is provided through the elimination of forced circulation instrumentalities comprising units or other mechanical parts.

Further objects of the invention will become apparent as the description proceeds, and the features of novelty will be pointed out in particularity in the appended claims.

The invention will be understood more readily by reference to the accompanying drawings, which illustrate one form of the invention embodying the improvements of the invention. In the drawings:

Fig. 1 is a transverse vertical sectional elevation of the device, the direction of air circulation being shown by arrows.

Fig. 2 is a fragmentary enlarged detail of one of the rilles and baffle plate.

Referring more particularly to the drawings, the improved construction of this invention comprises a cabinet A, the sides of which are provided with suitable heat insulation B. The cabinet A is formed interiorly with a top cooling

section 1 and a bottom warm air and storage compartment or section 2. The top cooling section contains an oversized cooling coil 3 which occupies the major portion of the space of the compartment, mounted intermediate the coil 3 and rear wall 4 of the cabinet and spaced from both is a substantially vertically disposed partition insulated wall 5 which extends longitudinally from end to end of the cabinet A but terminates short of the top 7 to form a space 6 and for enclosing the coil 3. The wall 5 defines a return air passage 8 between itself and the back wall 4 of the cabinet A, for directing the warm air from the warm air compartment through space 6 to coil 3, as will be pointed out further hereinafter.

The vertically disposed wall or splash plate 5 projects somewhat below the restricted throat 5' of the cooling section or compartment 1 and joins with the angularly disposed baffle plate section 9 which forms a continuation thereof and projects forwardly and downwardly therefrom. This baffle plate extends longitudinally through the cabinet A, and is secured to the end wall portions 10. The baffle plate 9 is provided with a plurality of longitudinally extending riffles 11 and terminates short of the bottom front portion 12 of the cabinet A. Mounted above the riffles 11 and slightly spaced therefrom is a reticulated open commodity holding and display screen 13, which is secured to the end walls and the front wall 12 of the cabinet A and extends upwardly and rearwardly to a point adjacent to the juncture of the members 5 and 9. The front of the display screen 13 abuts the front wall 12 in which is mounted the double wall transparent glass panes 14 which permits ready viewing of the fruits and vegetables displayed on the screen 13, which latter with said pane structure forms a display section 14'. Said section may be divided transversely into parallel separate compartment spaces for receiving the assorted fruits and vegetables.

It will be seen that the bottom warm air or storage compartment or section 2 is substantially deeper than the top cooling compartment or section 1 and that the front insulated wall section has a vertically depending top portion 15 and an inwardly inclined portion 16, which supports a reflecting mirror 17 that extends the length of the display cabinet A, the angularity of the mirror 17 being such as to reflect visibly to an observer facing the front of the cabinet the articles displayed on the screen 13. The end walls 10 are shaped somewhat symmetrically to the front vertical top wall portion 15 and the inwardly inclined wall portion 16 but project outwardly therefrom sufficiently to accommodate a mounting 18 for incandescent or fluorescent lights 19 which are disposed to illuminate the mirror 17 and the articles on the screen 13. As illustrating a suitable construction, the mirror 17 may be inclined at an angle from about 67 deg. to 75 deg. to the top inclined end portions 20 of the display section end walls 10, and the inwardly sloping portion 21 of the upper end walls 10 may form an angle of approximately 62 deg. thereto.

It has been stated that the cooling coil 3 which is located in the top of the cabinet A is an over-size coil, and occupies the major portion of the top compartment or cooling section 1, and in practice the cooling coil 3 has a B. t. u. capacity of substantially 50 per cent above the B. t. u. capacity of the compressor (not shown) which

operates the coil, the coil and the compressor being so proportioned that the coil condenses moisture from the surrounding air but without frosting. The resulting cooled air for example at a temperature of 34 deg. to 44 deg. being relatively heavy gravitates downwardly through the cooling section 1, and passes through the restricted throat of the cooling compartment 1 and is divided by the screen 13, a portion of the cool air passing beneath the screen 13 and over the riffled baffle plate 9 and the greater portion of this cool air passes over the screen 13 and throughout the commodities placed thereon. The baffle plate 9 is a continuous plate but terminates short of the front wall of the bottom section or compartment 2 to leave an opening 22 through which the air passes by gravity into the bottom compartment 2. This air has given up a portion of its cold and moisture to the fruit and vegetables on the screen 13, but has absorbed further moisture from the riffle held pools in passage 24 to maintain its moisture content and passes through opening 22 into the bottom warm air compartment from which it rises through passage 8 and passes into the cooling compartment and through the cooling coil 3. The air in the display cabinet A therefore is circulated continuously by convection currents and difference in densities between the cooled and warmer air. In practice, the air descending from the cooling coil 3 is approximately 15 degrees cooler than the ascending air currents.

This circulation is effected by convection currents set up by the difference in the specific gravities of the cooler air passing from the coil 3 and the relatively warmer air which ascends as the cooler air descends, and by the arrangement of the baffle plates. The screen 13 forms an opening 23 between its inner end and the vertical wall 5, the cool air from the coil 3 dividing so that a portion thereof passes over the screen 13 and a portion thereof passes through space 24 between the bottom of screen 13 and the top of the riffled baffle plate 9. The screen 13 and the baffle plate 9 are disposed close and substantially parallel to each other, and are inclined downwardly at an angle in excess of the normal angle of repose of the fruit and vegetables displayed on the screen 13, so that as such commodities are removed by the purchases of customers, the remaining commodities gravitationally move downwardly against the end glass abutment 14. This angle of inclination of the screen 13 and the baffle plate 9 also permits the heavier cool air to pass therealong as a slow but steady current above and around and in intimate contact with the commodities on screen 13. As these air currents reach the opening 22 between the outer end of the baffle plate 9 and front wall 12, the air current above the screen descending through and between the commodities to mix with the current in the space 24 between the screen 13 and the baffle plate 9, and this mixed air passes into the bottom compartment 2, it being now somewhat warmer so that it ascends through the rear passage or duct 8 that opens into the compartment 2. It will be understood that the passage 8 is of a size relative to the throat 5' to accommodate the ascending warm air from compartment 2. It is found in practice that virtually no outside atmospheric air mixes with the current of cool air passing downwardly over the screen 13, so that in practice a temperature differential of about 15 degrees is maintained between the descending cooler air and the ascending warmer air, a con-

tinuous, closed circulation cycle being thus maintained without forced draft circulating instrumentalities, as long as the coil 3 is operating.

It has been found in practice that a temperature of 44 deg. F., is the optimum temperature for the air passing from the coil 3, and the coil 3 is operated from such temperature to 34 deg. accordingly. This temperature effects condensation of moisture from the air circulating within the cabinet, and in accordance with this invention, this condensation is utilized for maintaining the displayed fruits and vegetables in a proper and attractive hydrated condition during the display thereof. The condensate on the coil 3 does not freeze owing to the temperature of the coil being above the freezing point of water, but it builds up until it drips continuously from the coil 3 against the inclined inner surface of the front wall portion 16 adjacent its lower end from which it is directed against the wall 5 by which it is splashed or diffused as it is directed through throat 5' and carried by the air currents over and through the commodities supported on screen 13 and displayed in section 14. Furthermore, a portion of this condensate from the coil 3 drops on the splash plate or wall 5 and flows therealong onto the baffle plate 9 and collects in pools behind the riffles 11. The air currents passing through the screen 13 and over the plate 9 reabsorb this condensate so that the moisture content of the air circulating in the cabinet A will be maintained substantially constant, and the commodities on the screen 13 will be maintained satisfactorily hydrated, without the necessity of recourse to water sprays or other extraneous source of water supply. If the humidity of the circulating air is very high, some condensate may collect in the bottom of the lower compartment 2, and consequently a trap 25 may be provided for withdrawing any such collected condensate.

The bottom compartment 2 is free from forced air-circulating instrumentalities or any other extraneous equipment and consequently may be utilized for storage purposes. A heat insulated door 26 may be provided for enabling access to be had to the interior of the compartment.

It will be seen from the foregoing description that the invention provides an improved open display cabinet which effectively displays and preserves food commodities which are maintained in a uniformly fresh and hydrated condition and readily accessible for self-service to customers, there being maintained a continuous circulation of humidified air over and around the commodities, the cabinet being free from moving parts or mechanism, or extraneous equipment. The illustrated embodiment of the construction which includes the features of the invention is a preferred form which has been accepted very popularly on the commercial market. However, it will be apparent that the improvements of the invention are not limited necessarily to the specifically illustrated and described embodiment, but structural details can be varied without departing from the spirit of the invention, and, accordingly, it will be understood and desired to embrace within the scope of the invention such modifications and changes as may be necessary to adapt it to varying conditions and uses, as defined in the appended claims.

Having thus described my invention, what I desire protected by Letters Patent is as set forth in the following claims:

1. An open top cabinet for displaying perishable food commodities, comprising a top com-

partment and a bottom compartment, air cooling means in the top compartment operated at a temperature below the dew point of air in the cabinet but above the freezing temperature of water, the cooling means producing active circulation of cooled and moisture-bearing air through the cabinet by convection currents maintained by differences in density between relatively cool and relatively warm air, an open display member for the commodities, means for directing convection currents of cool moisture-bearing air from the cooling means over and around the commodities on the display member, means for directing the currents of cool and partially de-humidified air downwardly by gravity into the bottom compartment after circulation around the commodities, and means communicating with the bottom compartment for leading convection currents of relatively warm air upwardly from the bottom compartment to the cooling means.

2. An open top cabinet for displaying perishable food commodities, which comprises in combination, a cabinet defining a top air-cooling compartment and a bottom compartment communicating with the top compartment, air cooling means in the top compartment operated at a temperature below the dew point of air in the cabinet but above the freezing temperature of water, the cooling means producing active circulation of cooled and moisture-bearing air through the cabinet by convection currents maintained by differences in density between relatively cool and relatively warm air, an open display member for the commodities communicating with the top compartment for receiving cooled air from the compartment, the said member sloping downwardly from the compartment at an angle enabling moisture-bearing cooled air to flow along the member by gravity and in intimate contact with commodities on the member for cooling and moistening the commodities, an air passageway communicating between the member and the bottom compartment for receiving gravitationally descending air currents from the commodities and for raising the temperature of the air slightly above the temperature of the descending air currents, thereby creating convection air currents in the cabinet, and means for leading convection currents of ascending warmer air currents into the cooling compartment, thereby continuously circulating cooled and moisture-bearing air over the commodities and through the cabinet while avoiding mechanical circulating instrumentalities.

3. A self-service cabinet for displaying and humidifying perishable food commodities, comprising a cabinet defining a top air-cooling compartment and a bottom compartment, air-cooling means in the top compartment operated at a temperature below the dew point of air in the cabinet but above the freezing temperature of water for collecting liquid water condensate on the cooling means, an open, reticulated commodity-displaying member communicating with the top compartment for receiving gravitationally descending cooled air therefrom and liquid condensate dropping from the cooling means, the said reticulated member sloping downwardly from the compartment at an angle enabling cooled air to flow gravitationally along the member and in intimate contact with commodities displayed thereon and to render such commodities fully visible to a purchaser, a baffle plate mounted adjacent to and beneath the reticulated

member and defining an air passage therebetween communicating with the top compartment, means in the top compartment adapted to direct cooled air and condensate from the cooling means onto the reticulated member and the baffle plate, a plurality of ripples on the baffle plate adapted to collect pools of condensate from the cooling means, the resulting pools of condensate being in contact with descending cooled and partially dehydrated air from the cooling means for humidifying the commodities and for re-humidifying the cooled air, the reticulated member and baffle plate terminating in a port communicating with the said air passageway and with the bottom cabinet compartment for gravitationally leading cooled and re-humidified air from the commodities into the bottom compartment for slightly raising the temperature of the air in the bottom compartment, and air duct means leading from the bottom compartment for enabling warmer air therein to rise by convection into the top compartment for re-cooling and gravitationally recycling the said air.

4. An open, self-service cabinet for displaying and humidifying perishable food commodities, which comprises, in combination, a cabinet having a closed top and a closed bottom, air-cooling means in the top of the cabinet operated at a temperature below the dew point of air in the cabinet but above the freezing temperature of water for condensing and collecting moisture from the air as liquid condensate, the cooling means producing active circulation of cooled and moisture-bearing air through the cabinet solely by convection currents maintained by differences in density between relatively cool and relatively warm air, a substantially vertically disposed splash plate mounted intermediate the cooling means and back of the cabinet and spaced from both, an open, reticulated commodity-displaying member angularly disposed downwardly from beneath the cooling means to a lower front wall of the cabinet, the said member having a slope enabling full viewing of the commodities thereon by a purchaser and enabling cooled air from the cooling means and liquid condensate directed against said splash plate to circulate by gravity over and around the commodities supported on the reticulated member to flow by gravity downwardly therethrough, a baffle plate disposed beneath the reticulated member and spaced therefrom in substantially parallelism therewith, the baffle plate being in engagement with the splash plate for also receiving a portion of the liquid condensate from the splash plate, means on the baffle plate for collecting liquid condensate in the space between the baffle plate and reticulated member, the said space defining a passage for convection currents of the cooled air descending from the cooling means in contact with the commodities, means enabling cooled air from the reticulated member and air passage therebeneath to pass by gravity to the bottom portion of the cabinet where the said air becomes somewhat warmer than the descending cooled air, and means for leading the resulting warmer air solely by convection upwardly from the bottom portion of the cabinet into engagement with the cooling means in the top portion thereof.

5. An open, self-service cabinet for displaying and humidifying perishable food commodities, which comprises, in combination, a cabinet having closed top and closed bottom portions, air cooling means in the top portion operated at a temperature below the dew point of air in the

cabinet but above the freezing temperature of water for condensing and collecting moisture from the air as liquid condensate, the cooling means producing active circulation of cooled and moisture-bearing air through the cabinet solely by convection currents maintained by differences in density between relatively cool and relatively warm air, a substantially vertically disposed splash plate mounted intermediate the cooling means and back of the cabinet and spaced from both, the said plate terminating short of both top and bottom of the cabinet, an angularly disposed surface forming with said splash plate a restricted passage below said cooling means, an open, reticulated commodity-displaying member angularly mounted on the cabinet and sloping downwardly and outwardly from beneath said restricted passage at an angle enabling full viewing of the commodities displayed thereon by a purchaser, said angularly disposed surface being adapted to direct the liquid condensate drippings from the cooling means against the splash plate from which a portion is directed into the path of the descending cool air and through said restricted passage and over and around said commodities humidifying the same, a baffle plate connected to said splash plate extending beneath said reticulated member and forming therewith a passageway through which is directed a portion of the condensate and air from the cooling means, means on the baffle plate for collecting pools of the liquid condensate, the resulting pools being engaged by air currents gravitationally passing through the reticulated member and the air passageway for re-humidifying the said air, the baffle plate defining a top closure for the bottom portion of the cabinet, and means enabling cooled and re-humidified air to pass by gravity from the reticulated member and passageway into the bottom portion of the cabinet where the air is warmed slightly to a temperature somewhat above the descending colder air, the said splash plate defining with the back of the cabinet an air duct for enabling the warmer air from the bottom portion of the cabinet to rise by convection into contact with the cooling means for recycling over the commodities.

6. A display cabinet, including an open top display compartment adapted to contain fresh food commodities, a cooling chamber above and in communication at its lower end with the display compartment, and a warm air chamber below the display compartment, an air return passage intercommunicating the warm air and cooling chambers, and a cooling means in the upper portion of said cooling chamber, the said cooling means producing active circulation of cooled and moisture-bearing air through the cabinet solely by convection currents maintained by differences in density between relatively cool and relatively warm air, whereby the air will be caused to circulate by convection from the warm air chamber to the cooling chamber, through the cooling means and pass over and through the contents of the display compartment, and into the warm air chamber, the cooling means being arranged so that condensate therefrom will be directed into the display compartment.

7. A display cabinet, including an open top display compartment adapted to contain fresh food commodities, a cooling chamber above and in communication at its lower end with the display compartment, and a warm air chamber below the display compartment, an air return passage intercommunicating the warm air and cooling

chambers, and a cooling means in the upper portion of said cooling chamber, the said cooling means producing active circulation of cooled and moisture-bearing air through the cabinet solely by convection currents initiated and maintained by differences in density between relatively cool and relatively warm air, whereby the air will be caused to circulate by convection from the warm air chamber to the cooling chamber, through the cooling means and pass over and through the contents of the display compartment and into the warm air chamber, said cooling chamber having a restricted passage at its lower end, the arrangement of said passage and the cooling means being such that the condensate from said cooling means is diffusely intermingled with the air particles and as they are directed into the display compartment.

8. An open, self-service cabinet for displaying and humidifying perishable food commodities, which comprises, in combination, a cabinet having closed top and closed bottom portions, air cooling means in the top portion of the cabinet and closely adjacent to the closed top thereof, the said air cooling means being operated at a temperature below the dew point of air in the cabinet but above the freezing temperature of water for condensing and collecting moisture from the air as liquid condensate, the cooling means producing gravitational circulation of air through the cabinet from top to bottom thereof by difference in density between relatively cool and relatively warm air, a substantially vertically disposed splash plate mounted in the cabinet intermediate the cooling means and back of the cabinet and spaced from both, the said plate terminating short of both top and bottom of the cabinet, an angularly disposed baffle plate forming with the splash plate a restricted passage below the cooling means, an open, reticulated commodity-displaying member angularly mounted on the cabinet vertically spaced above the baffle plate and defining a restricted space between itself and the baffle plate, the said reticulated member sloping downwardly and outwardly from beneath the restricted passage at an angle enabling full viewing of the commodities displayed thereon by a purchaser, the said angularly disposed baffle plate being adapted to direct liquid condensate dripping from the cooling means against the reticulated member from which a portion is directed over and around the commodities humidifying the same, means enabling cooled and re-humidified air to pass by gravity from the reticulated member into the bottom portion of the cabinet where the air is warmed slightly to a temperature somewhat above that of the descending colder air, the said splash plate defining with the back of the cabinet and air duct for enabling the warmer air from the bottom portion of the cabinet to rise by convection into contact with the cooling means for recycling over the commodities, continuous circulation of air being effected by convection only produced and continuously sustained by differences in specific gravity between the warmer ascending air and the cooler recooled and humidified air descending from the air cooling means in the top portion of the cabinet, the said recooled and humidified air passing solely by gravity downwardly from the cooling means and over and through the commodities being displayed, and reflecting means mounted longitudinally of the cabinet adjacent to the top thereof and in advance of the cooling means, the reflecting means being above the reticulated member and sloping at a complementary angle

thereto for reflecting an extended image of the commodities viewed by a purchaser, the reflecting means defining an outer front side of the cabinet.

- 5 9. An open top cabinet for displaying perishable food commodities, comprising a cabinet defining a top air-cooling compartment and a bottom compartment, air cooling means in the top compartment, the compartments being freely intercommunicating, an open reticulated commodity-displaying member communicating with the top compartment for gravitationally receiving cooled, moisture-bearing air therefrom, the said cooling means producing active circulation of 10 cooled and moisture-bearing air through the cabinet by convection currents maintained by differences in density between relatively cool and relatively warm air, the said reticulated member sloping downwardly from the top compartment 15 at an angle enabling cooled air to flow by gravity along the member and in intimate contact with the commodities displayed on the reticulated member, and to render such commodities fully visible to a purchaser, a baffle plate mounted to 20 and beneath the reticulated member and defining an air passage therebetween communicating with the top compartment, the reticulated member and baffle plate terminating in a port communicating with the said air passageway and with the bottom cabinet for slightly raising the temperature 25 of air therein, and air duct means leading from the bottom compartment to the top compartment for enabling warmer air in the bottom compartment to rise into the top compartment 30 through less specific gravity than the cooled descending air for recooling and gravitationally recycling the said air.
10. An open, self-service cabinet for displaying and humidifying food commodities, which comprises, in combination, a cabinet having closed top and closed bottom portions, air cooling means in the top portion of the cabinet and closely adjacent to the closed top thereof, the said air cooling means being operated at a temperature below the dew point of air in the cabinet but above the freezing temperature of water for condensing and collecting moisture from the air as liquid condensate, the cooling means producing gravitational circulation of air through the cabinet from top to bottom thereof by difference in density 40 between relatively cool and relatively warm air, a substantially vertically disposed splash plate mounted in the cabinet closely adjacent to the cooling means and back of the cabinet and spaced from both the said plate terminating short of both top and bottom of the cabinet, an open perforate commodity-displaying counter member angularly mounted on the cabinet and sloping downwardly and outwardly at an angle permitting full viewing of 45 the commodities displayed thereon, means directing condensate from the cooling means onto the commodities as cooled and dehumidified air from the cooling means descends gravitationally from the cooling means onto the commodities and flows over and through the commodities into the bottom portion of the cabinet, the commodity-displaying counter member communicating with the said bottom portion of the cabinet where the air is warmed slightly to a temperature somewhat 50 above that of the descending cooler air, the said splash plate defining with the back of the cabinet an air duct for enabling the warmer air from the bottom portion of the cabinet to rise 55 by convection into contact with the cooling means 60
